UNITED STATES PATENT OFFICE.

JOHN BRICKEN, OF CHICAGO, ILLINOIS.

DESIGN FOR A PENCIL.

Application filed January 20, 1923. Serial No. 4,950. Term of patent 14 years.

To all whom it may concern:

Be it known that I, JOHN BRICKEN, a citizen of the United States, residing at Chicago, in the county of Cook and State of Illinois, have invented a new, original, and ornamental Design for Pencils, of which the following is a specification, reference being had to the accompanying drawings, forming a part thereof.

Fig. 2 is a sectional view thereof, taken on the line 2—2 of Fig. 1.

I claim:—

The ornamental design for a pencil as shown.

In testimony whereof I have hereunto affixed my signature.

JOHN BRICKEN.
